UNITED STATES PATENT OFFICE

GEORGE P. MARSHALL, OF WASHINGTON, DISTRICT OF COLUMBIA

DESIGN FOR STORE

Application filed January 23, 1931. Serial No. 38,432. Term of patent 14 years.

To all whom it may concern:

Be it known that I, GEORGE P. MARSHALL, a citizen of the United States, residing at Washington, in the District of Columbia, have invented a new, original, and ornamental Design for Store, of which the following is a specification, reference being had to the accompanying drawing, forming part thereof.

Fig. 1 is an elevational view of the front of the store, and

Fig. 2 is a perspective view of the interior of a store showing my new design.

I claim:

The ornamental design for store as shown.

GEORGE P. MARSHALL.
